UNITED STATES PATENT OFFICE.

THOMAS W. BEAL, OF SANDWICH, ILLINOIS, ASSIGNOR TO THE SANDWICH ENTERPRISE COMPANY, OF SAME PLACE.

CULTIVATOR.

SPECIFICATION forming part of Letters Patent No. 380,783, dated April 10, 1888.

Application filed March 22, 1887. Serial No. 231,933. (No model.)

To all whom it may concern:

Be it known that I, THOMAS W. BEAL, of Sandwich, in the county of De Kalb and State of Illinois, have invented certain new and 5 useful Improvements in Cultivators, of which the following is a description, reference being had to the accompanying drawings.

My invention relates to wheel-cultivators; and the primary object of the invention is to 10 provide novel coupling mechanism between the cultivator-beams and the wheel-axles, which permits of such connection with springs or with the draft that either or both of these instrumentalities may be made to assist in lifting 15 the hoes above the ground, or in forcing them into the ground; also to provide means especially adapted to this class of cultivators for equalizing the draft on the horses, and to produce such other useful results as will be pointed 20 out herein.

To these ends it consists in the construction and combination of parts herein fully described, and pointed out definitely in the claims.

25 In the drawings, Figure 1 is a side elevation of my improved cultivator. Fig. 2 is a transverse vertical section of the upper part of the machine on line 2 in Fig. 1, looking toward the rear end thereof. Fig. 3 is a side view of the 30 coupling mechanism with the wheel cut off. Fig. 4 is a front view of said coupling mechanism. Fig. 5 is a horizontal section on the line 5, and Fig. 6 is a perspective view of the mechanism for equalizing the draft.

35 Referring to the parts by letters of my invention shown in said drawings, A represents the tongue, which extends backward to form an important part of the main frame.

B represents a cross-bar, which is rigidly secured to said tongue at right angles thereto. The bars or supports C C and C' C' are adjustably secured to said cross-bar B, preferably in the manner shown, to wit: Their upper ends are provided with transverse bearings c², which 45 slip over the cross-bar B, one pair of supports, C C, being on one side of the tongue and the other pair, C' C', on the other side thereof, and they are prevented from revolving or from moving laterally by the set-screws c c. If de- 50 sired, their revolution may be prevented by making the cross-bar B angular in cross-sec-

tion and giving to the bearings in the supports C C' the same form. In the lower ends of the supports C C' are bearings c³, in which the wheel-axles D D are loosely mounted, while 55 the wheels F F are loosely mounted on the outer ends of said axles.

Between the lower ends of the supports C C a coupling, E, having the rearward projections, G G, is rigidly secured to each axle. These 60 couplings E prevent the axles from slipping out of their bearings, and, if desired, may be integral parts of the axle to which they are secured; but, for convenience in setting up the machine, I prefer that they be made in separate pieces and secured together by means of a set-screw, d, or other appropriate means. The rearward projections, G G, are adapted to be connected with the forward ends of the cultivator-beams I by means of the vertical 65 pivot-bolts i.

An arm, e, extends upward from the coupling E, and is rigidly secured thereto. The upper ends of each pair of supports C C C' C' are preferably rigidly connected together by a short 70 arm, c', and to this arm a bent spring, H, is attached on each side of the machine. The lower ends of these springs are bent backward, and are connected by the links h to the arms e. The force of the springs is always exerted to 75 draw said arms forward, thereby acting against the weight of the cultivator-beams and assisting in lifting and handling them. An arm, e', is also secured to the coupling E, and may project both downward and upward therefrom. 80 The draft rod or chain J is preferably secured to this arm e', and when secured below the axle the effect of the draft is to force the hoes into the ground and to hold them there when the cultivator is in motion. A number of eyes, 85 e² e², are provided in said arm, and the draft-rod may be secured in any one of these. The farther the point of attachment is below the axle D the greater will be the force with which the hoes are pressed into the ground. If it is 90 not desired that any of the draft shall be used for this purpose, the rods J may be attached to the eye e² in line with the axle. If it is de- 95 sired that the draft shall in a measure assist in lifting the cultivator-beams, the rod J may be 100 attached to an eye above the center of the axle.

The coupling E, the projections G, the arms

- e and e', and the axle D may be made as separate pieces; but it is necessary that in operation they shall be rigidly secured together, so that any movement of one shall produce a corresponding movement of all the others. In practice I prefer to make the axle in one piece, and the coupling, projections, and arms in another piece, and secure them together by means of a set-screw, d, or other appropriate means.
- 10 In operation, when the beams are lifted or depressed, the axles D turn in their bearings without affecting in any way the motion of the wheels. The beams are also permitted a lateral movement, swinging on the pivot-bolt i.
- 15 It will be noticed that the draft-rods J are attached directly in front of the beams I, and that the pull is in line with said bars; or, in other words, each horse pulls directly in line with the resistance. The effect of this is that 20 the wheels and frame are pushed ahead of the beams and much of the strain upon connecting devices is obviated.
- 25 The distance between beams may be varied, thereby adapting the cultivator for use with all widths of planting, and this change is accomplished by loosening the set-screw c and sliding the supports C C and C' C' along the cross-bar B, fastening them at the desired point. This movement of the supports C C' causes a 30 like movement of the coupling and all the parts connected therewith, thereby varying the distance between the furrows, but retaining the parts in the same relative position, to operate as described above.
- 35 M represents a cross-bar secured to the tongue A, and N a doubletree or evener pivotally secured to said tongue in front of said bar M. Pivoted to the bar M are the arms m m, and depending loosely from the doubletree 40 N are the arms n n. The arms m are preferably bent forward at their middle points, and the links m' m' connect the arms m and n near their middle points. The draft-rods J are secured to the lower end of the arms M, and the 45 pull of the machine is transmitted by means of the links m' to the middle of the arms N. The horses are attached to the lower ends of the arms n. By this arrangement the draft of the horses is equalized to a greater extent and

a greater freedom of motion allowed the horses 50 than in other devices without affecting materially the relative amount of work performed. The lower end of one of the arms N will move forward as far as the evener on that side moves rearward when the horse attached on that side 55 moves ahead of its mate. In other devices, when the horse is attached to a depending rod between the evener and the points where the draft-rod is attached, the horse can move only partly as far as the evener moves without increasing his work. The draft-rod J might be attached directly to the middle of the arm N if the couplings E were high enough; but in machines as ordinarily constructed the arms 60 M are necessary to transmit the draft horizontally instead of at an angle.

Having thus described my invention, what I claim as new, and desire to secure by Letters Patent, is—

1. The combination of a rigid cross-bar and 70 supports adjustably secured thereto having bearings in their lower ends, and springs secured to said supports with short axles loosely mounted in said bearings, means for securing the cultivator-beams to said axle, arms extending upward from said axles and rigidly connected therewith, and connecting devices between said arms and springs, substantially as and for the purpose specified.

2. In a cultivator, short axles loosely mounted 80 in suitable bearings having rearward-projecting coupling-jaws rigidly secured to said axles, combined with means for attaching the draft directly to said axles, or some part rigidly connected therewith, substantially as and for the 85 purpose set forth.

3. The combination of the tongue, a cross-bar rigidly secured thereto having pivoted to each end a depending arm with an evener pivoted to said tongue, an arm loosely depending 90 from each end thereof, and links which connect the depending arms on each side of the tongue together near their middle points, substantially as and for the purpose specified.

THOMAS W. BEAL.
